HARRY C. HEATH, OF SAN FRANCISCO, CALIFORNIA.

SIREN.

1,238,291.

Specification of Letters Patent. Patented Aug. 28, 1917.

Application filed July 13, 1915. Serial No. 39,584.

To all whom it may concern:

Be it known that I, HARRY C. HEATH, a citizen of the United States, residing in the city and county of San Francisco and State 5 of California, have made a new and useful invention—to wit, a Siren; and I do hereby declare the following to be a full, clear, concise, and exact description thereof.

The invention is an improvement on my 10 siren disclosed in Letters Patent No. 1,086,822, of February 10, 1914.

The invention contemplates a siren with improved valve mechanism for controlling the admission and escape of air respectively 15 to and from the siren runner, whereby the siren is enabled to produce its maximum sound or to cease its sound immediately.

Referring to the annexed drawing which forms a part of this specification.

20 Figure 1 is a vertical longitudinal sectional view of a siren embodying my invention with the air inlet and outlet valves open.

Fig. 2 is a view similar to Fig. 1 with the 25 air inlet and outlet valves closed.

Fig. 3 is a horizontal sectional view taken on line x^3-x^3 of Fig. 1, looking downwardly.

Fig. 4 is a horizontal section taken on 30 line x^4-x^4 of Fig. 1 and looking upwardly.

Fig. 5 is a horizontal sectional view taken on line x^5-x^5 looking downwardly.

The siren comprises a runner 1, inclosed within a casing 2, which casing is mounted 35 upon a hollow base 3. Said casing consists of a lower horizontal wall 4, vertical cylindrical wall 5, conical wall 6 which converges upwardly, vertical cylindrical bearing wall 7 and upper horizontal wall 8.

40 The casing 2 is provided with a plurality of radial inlet openings 9 in the conical wall 6, through which air may enter the casing, and a plurality of circumferential openings 10 in the vertical cylindrical wall 5 through 45 which the air which enters the casing through said inlet openings may escape from the casing during the operation of the runner as will be hereinafter more fully disclosed. The runner 1 is mounted upon a vertical shaft 11 journaled in ball bearing 12 within a hub 13 depending from the wall

4, the axis of said bearing and hub being in alinement with the bearing wall 7. The shaft 11 is coupled by means of coupling 14 to motor shaft 15 of motor 16 which is 55 mounted within the hollow base 3. The runner 1 is provided with a central air inlet 17 through which the air in the casing 2 enters the runner and a plurality of radial air passages 18 which communicate with 60 said air inlet at their inner ends and are adapted to communicate successively with the outlets 10 in the vertical casing wall 5, when the runner is rotated, so that the air may escape intermittently from the runner 65 through said outlets. An upwardly converging sound box 20 incloses and extends above the conical wall 6 and upper part of the casing 2. The casing 2 is preferably 70 formed in two separate sections, an upper and a lower section, the conical wall 6, vertical cylindrical wall 7 and upper horizontal wall 8 forming the upper section and the vertical cylindrical wall 5 and lower horizontal wall 4 forming the lower section 75 thereof. The sound box 20 is preferably formed integral with the upper section of the casing. The lower section of the casing is provided with an annular horizontal flange 21 extending outwardly from the top 80 of the vertical cylindrical wall 5, and the upper section of the casing is provided with an annular flange 22 extending outwardly from the sound box 20 which flange 22 is adapted to rest upon the flange 21 whereby 85 the upper section of the casing and the sound box are supported upon the lower section of the casing. Bolts 25 extend through the flange 22 and screw into the flange 21 and detachably secure the upper section of 90 the casing and the sound box to the lower section of the casing. A trumpet 30 is detachably connected to the top of the sound box 20 by means of flanges 31 and 32 on the top of the sound box and lower end of the 95 trumpet respectively, and bolts 35 which extend through flange 32 and screw into flange 31. An air inlet valve is provided for controlling the feeding of the air to the interior of the casing 2 and the runner 1. 100 Said valve comprises the conical wall 6 and inlet openings 9 and a valve shutter 40

which rests within the casing 2 adjacent the conical wall 6. Said shutter is provided with radial openings 41 and radial closing members 42 adapted respectively to register 5 with the inlet openings 9 to establish or shut off communication through the inlets between the sound box 20 and the interior of the casing 2 in the manner hereinafter more clearly described. An air outlet valve 10 is provided for the escape of air from the outer ends of the radial passage 17 of the runner 1 through the outlets 10. Said valve comprises the vertical cylindrical wall 5 and its outlet openings 10 and a shutter 50 which 15 rests within the casing adjacent the wall 5. Said shutter comprises a plurality of openings 51 and a plurality of closing members 52 adapted respectively to register with said outlet openings 10 to establish or shut 20 off communication of the outer ends of the runner passages 17 with the atmosphere through the outlets 10 in the manner hereinafter more fully disclosed. The valve shutters 40 and 50 are preferably formed in 25 one piece so that they may turn together and open or close the inlets 9 and outlets 10 at the same time. Arms 55 depend from the shutter 50 through slots 56 in the lower horizontal wall 4 and are bolted by bolts 30 57 to the ends of a yoke 58 which is journaled on hub 13 whereby said shutters are journaled upon said hub. A cap 58^x screws on the end of the hub 13, which closes the lower end of the hub and bears against the yoke 35 58 so as to hold the yoke properly on the bearing on said hub. The conical shutter 40 has a trunnion 59 extending upwardly therefrom and journaled within the cylindrical bearing wall 7, whereby the shutters 40 and 50 are journaled in said bearing wall. The trunnion 59 has a top wall 60 provided 40 with an opening 61 through which extends a bolt 65 which bolt extends upwardly through and screws into a shutter end 45 thrust bearing 66, which bearing extends through and screws into the upper end casing wall 8 and embossment 67 formed on said casing wall. The bolt 65 has a head 68 on its lower end between which and the 50 upper trunnion wall 60 rests a coil spring 70, which spring tends to force the shutters upwardly and the shutter 40 against the conical valve casing wall 6. One end of 55 said spring 70 is connected to the trunnion top wall 60 and the other end is connected to the head 68 whereby the bolt 65 is prevented from turning except under considerable tension of the spring. A nut 75 screws on the upper end of the bolt 65 60 against the upper end of the end thrust bearing 66 by means of which the bolt and head may be drawn upwardly and the upward pressure of the spring against the trunnion top wall 60 and the upward pres-

sure of the shutters increased. The nut 75 65 may be pinned to the bolt 65 by pin 76 so as to lock the spring 70 at its desired tension when so adjusted. A nut 80 is provided at the upper end of end thrust bearing 66 by means of which said bearing may be turned 70 and screwed against or away from the trunnion top wall 60 so as to move the shutter 40 axially away from or toward the conical wall 6 and provide the proper fit of the shutter 40 and conical wall 6 with relation to each other. The cap 58^x is turned on the hub 13 to permit axial movement of the yoke 58, arms 55, shutters 50 and the axial adjustment of the shutter 40. A lock nut 85 screws on the end thrust bearing 66 80 against the embossment 67, whereby said bearing may be locked to hold the shutter in its properly adjusted position. A connection 90 is connected to the yoke 58 by means of which the yoke and the valve shutters 40 and 50 are oscillated on their bearings 7 and 13.

The operation of the siren is as follows:

The runner 1 is rotated by the motor 16 while the inlets 9 and outlets 10 are open, air 90 from the atmosphere enters the upper open end of the trumpet 30 and passes through the inlets 9 into the casing 2 and through runner inlet 17 into the runner passages 18 and the centrifugal force created in said 95 passages by the rotation of the runner forces the air in the runner through said passages toward the circumferential casing wall 5 and out of the runner and casing 2 through outlets 10. The outflow of the air through the outlets 10 is intermittently interrupted by the portions of the wall 5 between said outlets, and during such outflow interruptions of the air said wall portions reflect the siren sound out of the runner and casing 2 100 through runner inlet 17 and casing inlets 9 and thence through the trumpet 30 which magnifies the sound, and out of the upper open end thereof. Upon turning the shutters 40 and 50 so that the shutter closing members 42 and 52 close the inlets 9 and outlets 10 respectively, the runner 1 is completely isolated so that no air can enter the runner or pass therefrom. The isolation of the runner prevents the siren from producing sound. The length of the slots 56 is such that when the arms 55 engage one end of the slots the shutter openings 41 and 51 register with the inlets 9 and outlets 10 and open the air inlet and outlet valves, and when the arms engage the other end of said slots the shutter closing members 42 and 52 register with and close the said inlets and outlets by oscillating the shutters upon their bearings the air inlets and outlets may be immediately opened and closed and the sound of the siren immediately produced at full blast or completely eliminated. The in-

terval of oscillation of said shutters determines the intervals of sound and the intervals of silence or the "characteristic" of the siren.

5 I claim:

1. In a siren a runner, a casing inclosing said runner, a conical inlet wall forming part of said casing, a conical air inlet valve shutter controlling the inlet in said conical

10 inlet wall, an air outlet wall forming part of said casing, a valve shutter controlling the outlet in said outlet wall and means for adjusting said inlet shutter axially with relation to said conical inlet wall.

15 2. In a siren a runner, a casing inclosing said runner, air inlet and outlet valves in said casing, a bearing upon which said inlet valve is journaled, said casing provided with a pair of slots, arms on the shutter of 20 said outlet valve, projecting through said slots, a yoke connected to said arms, and a bearing upon which said yoke is journaled.

25 3. In a siren a runner, a casing inclosing said runner, air inlet and outlet valves in said casing, a bearing upon which said inlet valve is journaled, said casing provided with a pair of slots, arms on the shutter of said outlet valve projecting through said slots, a yoke connected to said arms, a bearing upon 30 which said yoke is journaled, and means for adjusting the shutter of said inlet valve and said yoke axially upon their bearings.

35 4. In a siren a runner, a casing inclosing said runner, air inlet and outlet valves in said casing, a bearing upon which said inlet valve is journaled, said casing provided with a pair of slots, arms on the shutter of said outlet valve projecting through said slots, a yoke connected to said arms, a bearing upon 40 which said yoke is journaled, a nut screwing on the end of said yoke bearing and adapted to permit axial adjustment of said yoke on said bearing and means for adjusting the shutter of said inlet valve and said yoke axially on their bearings.

45 5. In a siren a runner, a casing inclosing said runner, an inlet valve wall and an outlet valve wall forming part of said casing, an inlet valve shutter and an outlet valve shutter controlling respectively the inlet and outlet of said inlet and outlet walls, a spring bearing axially against said inlet valve shutter and tending to urge said 50 shutter axially toward said inlet valve wall, and means for varying the tension of said spring.

60 6. In a siren a runner, a casing inclosing said runner, an inlet valve wall and an outlet valve wall forming part of said casing, an inlet valve shutter and an outlet valve shutter controlling respectively the inlet and outlet of said inlet and outlet walls, a spring bearing axially against said inlet

valve shutter and tending to urge said shutter axially toward said inlet valve wall, and an adjustable end thrust bearing adapted to adjust said inlet shutter axially away from said inlet wall against the tension of said spring.

65 7. In a siren a runner, a casing inclosing said runner, an inlet valve wall, and an outlet valve wall forming part of said casing, an inlet valve shutter and outlet valve shutter controlling respectively the inlet and outlet in said inlet and outlet walls, an end thrust bearing screwing into said casing against said inlet shutter and adapted to adjust said shutter away from said inlet wall, a bolt extending through and screwing into said end thrust bearing, a head on the inner end of said bolt, a spring between said bolt head and inlet shutter and a nut screwing on the outer end of said bolt against said end thrust bearing.

70 8. In a siren a runner, a casing inclosing said runner, an inlet valve wall and an outlet valve wall forming part of said casing, a bearing wall forming part of said inlet valve wall, an inlet valve shutter and an outlet valve shutter for respectively controlling the inlet and outlet of said inlet and outlet walls, a hollow trunnion formed on said inlet shutter, an end wall extending across the upper end of said trunnion, and an end thrust bearing screwing into said casing against said trunnion end wall and adapted to adjust said shutter away from said inlet wall, a bolt extending through and screwing into said end thrust bearing, 90 a head on the inner end of said bolt, a spring between said bolt head and said trunnion end wall, and a nut screwing on the outer end of said bolt against said end thrust bearing.

95 9. In a siren a runner, a casing inclosing said runner, a conical inlet wall forming part of said casing, a conical air inlet valve controlling the inlet in said inlet wall, an air outlet wall forming part of said casing, a valve shutter controlling the outlet in said outlet wall, said inlet and outlet shutters being alined so as to open or close the said inlets and outlets at the same time.

100 10. In a siren, a runner, a casing inclosing said runner, an air inlet and an air outlet valve in said casing, a bearing in which the shutter of said inlet valve is journaled, said casing provided with slots, arms on the shutter of said outlet valve, a hub extending from said casing, a yoke journaled on said hub and connected to said arms, a ball bearing in said hub upon which said runner is journaled and a cap screwing on the end of said hub inclosing said ball bearing 115 and bearing against said yoke.

11. In a siren a runner, a casing inclosing said runner, an air inlet valve journaled in

said casing, an air outlet valve in said casing adapted to operate with said inlet valve, means for adjusting said inlet valve axially, said casing provided with slots, arms on said outlet valve extending through said slots, a hub on said casing, a yoke journaled on said hub and connected to said arms, and a cap screwing on said hub against said yoke.

In testimony whereof, I have hereunto set my hand at San Francisco, California, this 6th day of July, 1915.

HARRY C. HEATH.

In presence of—

ALAN FRANKLIN,
JOSEPHINE TUNIS.
